UNITED STATES PATENT OFFICE.

RALPH R. REED, OF MORGAN HILL, CALIFORNIA.

AEROPLANE.

1,354,002.

Specification of Letters Patent. Patented Sept. 28, 1920.

Application filed July 10, 1919. Serial No. 309,801.

To all whom it may concern:

Be it known that I, RALPH R. REED, a citizen of the United States, residing at Morgan Hill, in the county of Santa Clara and State of California, have invented certain new and useful Improvements in Aeroplanes; and I do declare the following to be a full, clear, and exact description of the invention, such as will enable others skilled in the art to which it appertains to make and use the same.

This invention relates to aeroplanes, and it relates more specifically to an improved propelling and guiding means, and an improved aeroplane in which its truck is reversible with relation to its main body portion.

Another object is to provide an improved device of this character which is useful as a primary training device for students of aviation, also as an amusement device or toy.

A further object is to provide an improved device of this character with flexible guiding means which permit limited upward and lateral movements of the aeroplane while continually resisting such upward and lateral movements and tending to hold the aeroplane in a level position and to return the aeroplane to its normal or straight path of movement.

A further object is to provide a device of this character which is exceedingly simple, and which is comparatively inexpensive to manufacture, install and operate.

Other objects and advantages may become apparent to persons who read the following details of description in connection with the accompanying drawings, in 40 which:—

Figure 1 is an end elevation illustrating my improved aeroplane and its guiding and propelling means, the dotted lines illustrating how the aeroplane may be deflected laterally by wind or by the operation of the aeroplane itself.

Fig. 2 is a side elevation showing the aeroplane in its normal position and in a position above normal, the dotted lines illustrating the latter position.

Fig. 3 is a top plan view illustrating how the device permits the aeroplane to be deflected laterally, or in other words, this

figure shows, in plan, what is shown by Figs. 1 and 2 in elevation.

55

Fig. 4 is a side elevation of a somewhat modified form of the invention.

Fig. 5 is a top plan view of the modification shown in Fig. 4.

Fig. 6 is a fragmental detail view illustrating the connection of the guides or guiding cables in the modified form illustrated in Figs. 4 and 5.

Fig. 7 is a detail view, in side elevation, illustrating the details of my improved aeroplane more clearly.

Fig. 8 is a fragmentary top plan view of the aeroplane shown in Fig. 7.

Fig. 9 is a vertical sectional view, the section being taken substantially along the line 70 9—9 of Fig. 7.

Fig. 10 is a vertical sectional detail view, the section being taken substantially along the line 10—10 of Fig. 8.

Referring to these drawings in detail, in which similar reference characters correspond with similar parts throughout the several views, and in which the body portion 11 of the aeroplane may be of any appropriate construction, and may comprise the planes 80 12, rudder 13 and propeller 14.

A truck 15 may be pivotally connected to the body 11 by means of a pivot 16, so that the main body portion of the aeroplane may be reversed with relation to the truck, 85 for a purpose which will hereinafter become apparent. A reversing lever 17 may be provided on the lower part of the main body portion, and a latch 18 may be carried thereby, said latch being engageable 90 with a keeper 19 which is carried by one of the laterally extending arms 20 which is united with and constitutes an element of the truck. Eye members or guide-engaging members 21 are carried respectively 95 by the ends of the arms 20, and guides or guiding cables 22' may either extend through and be movable in the eye members 21, as in the modified form shown in Figs. 4, 5 and 6, or similar guides 22 may 100 be fixed to the members 21, respectively, as indicated at the lower part of Fig. 8.

Referring now to Figs. 1, 2 and 3, it will be seen that the cables 22 are substantially endless, each having its ends connected to 105 the same eye member 21, while intermediate

portions of each cable 22 pass around grooved rotors or drums 23 which are supported in bearings 24 at the ends of a track 25. This track may be formed either of 5 wood, earth, or any appropriate material, and the truck 15 may roll along this track or rest thereon, and it may be driven either by its own motive power, through the medium of the propeller 14, or it may be 10 drawn along the track by means of the cables 22. Any appropriate number of the cables 22 may be employed, three being illustrated in Figs. 1, 2 and 3, so that if one of the cables should break, the two remaining 15 ones are sufficient to hold the aeroplane substantially in an upright position. Moreover, one endless cable 22 will ordinarily suffice by substituting the non-endless cables 22' for the outer ones of the three cables, as 20 illustrated in Fig. 5 in which case these outer cables will be made to pass through guiding rings attached to the machine instead of being fixed to the said machine as in the case when these outer cables are 25 endless in form. It will be seen that guide-supports 26 support the ends of the cables 22' and hold these cables stretched therebetween. Moreover, the middle cable 22 preferably has its ends connected to the 30 front and rear ends of arms 27 which are fixed on the truck 15 and extend at right angles to the arms 20, and therefore, the middle cable is also substantially endless, for the arms 27 may be considered a continuation of the cable. In this connection, 35 it should be understood that the doctrine of equivalents applies, and that it is not intended to limit this invention to the use of cables as the elements 22 and 22', as wire, cord, or other flexible and somewhat elastic guides 22 and 22' may be employed, according to whether this device is used as a training device or a toy, etc.

In the form shown in Figs. 1, 2 and 3, 40 motors 28 or other appropriate means may be employed for rotating the rotors 23, and these motors may be reversible, or one may be employed for rotating the rotors in one direction, and the other may be employed for rotating them in the opposite direction, 45 clutches 29 being provided when desirable. Therefore, it will be seen that the truck 15 is always held against turning with relation to the track 25 and the guides adjacent 50 to the track, but the body portion of the aeroplane may be turned by means of the arm or lever 17, with relation to the truck, so that the aeroplane moves forward whether 55 going toward one end or the opposite end of the track. Fig. 10 illustrates the two cam surfaces 29 on the keeper 19, which raise the latch 18, so that the main body portion is 60 automatically locked with relation to the truck when it has been reversed.

65 The distance between the rotors or sup-

ports 23 is preferably about six hundred yards, when the device is used for purposes other than a toy, and although this distance may be widely varied, it should be sufficient to permit the inherent elasticity of 70 the wires or cables to permit the aeroplane to move upward or laterally a considerable distance, but the elasticity of the wires or cables continually tends to draw the aeroplane into its normal path of movement. 75

Although I have described this invention very specifically, it is not intended to limit this invention to these exact details of construction and arrangement, but changes may be made within the scope of the inventive 80 ideas, as implied and claimed.

What I claim as my invention is:

1. The combination of an aeroplane provided with cable-guides, and guiding cables passing through said cable-guides and permitting the aeroplane to travel therealong while continually resisting lateral and vertical movements of the aeroplane, each of the cables being supported substantially at the ends of the normal path of travel of the 90 aeroplane, said cables being sufficiently long and elastic to permit them to be deflected a considerable distance laterally and vertically of the said normal path while continually tending to hold the aeroplane parallel 95 to the earth (or level) and return said aeroplane to said normal path.

2. The combination of an aeroplane provided with cable-guides, guiding cables passing through said cable-guides and permitting the aeroplane to travel therealong while continually resisting lateral and vertical movements of the aeroplane, each of the cables being supported substantially at the ends of the normal path of travel of 100 the aeroplane, said cables being sufficiently long and elastic to permit them to be deflected a considerable distance laterally and vertically of the said normal path while continually tending to hold the aeroplane 105 level and return said aeroplane to said normal path, and means including a cable to propel the aeroplane along the first said cables, said means also being coöperative with the first said cables for returning said aeroplane to its normal path. 110

3. The combination with an aeroplane provided with cable-guides, of rotors, a substantially endless cable extending around and movable longitudinally by said rotors, 120 said cable being connected to said aeroplane in such relation that it pulls said aeroplane therealong, and a pair of guiding cables passing through said cable-guides and permitting the aeroplane to travel therealong 125 and be guided thereby while permitting a limited lateral and vertical deflection of the aeroplane from its normal path of travel.

4. The combination of an aeroplane comprising a truck, a track on which the truck 130

is mounted to travel, guide-supports at the ends of said track, a guiding cable connected to and stretched between said guide-supports and also connected to said aero-
5 plane in such relation that the truck may travel on said track and also travel above said track, said cable being sufficiently long

and elastic to permit it to be deflected upward and laterally while tending to return the aeroplane to said track.

10

In testimony whereof I have hereunto set my hand.

RALPH R. REED.
